GOLF BALL HEATER

Robert S. Goodrich, 27901 S. Golden Meadow Drive,
Palos Verdes Peninsula, Calif. 90274

Filed Sept. 13, 1972, Ser. No. 288,732

Term of patent 14 years

Int. Cl. D23—03

U.S. Cl. D23—77

FIG. 1 is a perspective view of a golf ball heater showing my new design;

FIG. 2 is a front elevation thereof;

FIG. 3 is a right side elevation thereof;

FIG. 4 is a top view thereof;

FIG. 5 is a bottom view thereof;

FIG. 6 is a back side elevation thereof.

I claim:

The ornamental design for a golf ball heater, substantially as shown.
